UNITED STATES PATENT OFFICE.

RUDOLPH KRETER, OF NEW YORK, N. Y., ASSIGNOR TO NUNNS & CLARK.

COVERING PIANOFORTE-HAMMERS.

Specification of Letters Patent No. 9,526, dated January 4, 1853.

To all whom it may concern:

Be it known that I, RUDOLPH KRETER, of the city and county of New York and State of New York, have invented certain new and useful Improvements in Machinery for Covering the Hammers of Pianofortes; and I do hereby declare that the following is a full, clear, and exact description of the same, reference being made to the annexed 10 drawings, making a part of this specification, in which—

Figure I is a side view; Fig. II a top view; Fig. III an end view; Fig. IV a longitudinal vertical section; Fig. V a transverse section; Figs. VI, VII and VIII, are parts in detail, and similar letters refer to similar parts throughout.

In the manufacture of pianofortes one of the most delicate, difficult and tedious parts 20 is the covering of the hammers. Few workmen comparatively attain excellence in this department. The requisites in a good set of hammers are that they should have regular 25 graduations of thickness, hardness and weight, the greatest hardness, least thickness and weight at the highest part of the scale or treble; and increasing from note to note with a regular and equal succession to the lowest. The covering material is applied with glue, and, as in the old mode, 30 each hammer is done separately by hand, the workman has no guide to the obtaining of the above requisite except his skill. Hence there are always many condemned 35 hammers which have to be replaced on the trial of them by the "regulator" of the instrument.

My invention has for its object the covering 40 of the hammers in a connected set; the several thicknesses or coats being applied one after the other but to the whole set at once. My machine produces perfect regularity in the graduations of hardness of the hammer and this is effected by the degree of 45 tension with which the felt is stretched over the piece of wood called the "hammer head", and may be adjusted and graduated from end to end as desired. It insures the perfect gluing of all parts of the surface 50 supplied with that material; it effects a large saving in material and time besides producing a superior tone in the instrument, for there are no, unequal or false notes, 55 since there is no irregularity in the rate or degree of hardness in the hammers.

In using my machine I propose to employ felt as the covering material. For this purpose the article is manufactured in sheets of a width equal to the length of the strip required and of unequal thickness, one edge 60 being twice or three times the thickness of the other edge, the thickness diminishing by a gradual taper. The hammer heads are formed out of a wedge like strip of wood, being thicker at one end than the other, the 65 strip being long enough to be cut into a sufficient number of pieces to form a set. In sawing the heads out each is numbered, so as to insure the same relation that they had in the strip. This is necessary because the 70 bass hammers are heavier than the treble.

The covering consists of three thicknesses at the base, gradually tapering to two toward the middle, and continuing double to 75 the end. To prepare the covering a narrow strip proper for the innermost coat is cut from a sheet of felt prepared as described, and of sufficient length to cover as many hammer heads as required, say for one-third 80 from the base up; this is then shaved down along each of its edges to a feather, leaving the thickest part in the middle, as seen by the cross section in Fig. VI of details, at (a). The next coat is prepared in like manner, but extending to the whole length required to form the set, and lastly the third 85 coat.

To cover the hammers by my machine: First the several distinct pieces composing 90 the set of hammer heads are to be arranged in their proper order in a clamp. This is a strong bar A consisting of two pieces, or plates, which are attached parallel to each other by bolts and nuts. One plate is flanged at the top edge and the two ends terminate in dovetails to fit a dovetail groove 95 in the upright guides as seen at (c) Fig. II. This clamp extends across the top of the machine, as shown, and fits in a dovetail formed in the top of two uprights, where it is permanently keyed. The uprights themselves are made so as to slide up and down and in doing so carry with them the clamp 100 in a manner to be described. The clamp A must be taken out of the machine to fit the hammer heads into it. This is done by loosening the nuts on the bolts (d) whereby the plate (d') Fig. V, will be allowed to open and form a space between the two. The 105 hammer heads are then arranged in this 110

space in the order of their numbers, as seen at (e), and full size at Figs. VI and VII. The nuts are then screwed hard up and the hammer heads firmly clamped between the plates ready to be introduced upon the machine.

5 The next operation is to place the prepared felt for the covering upon the machine. The parts intended to effect this operation consist of a frame or carriage which slides down between the lips of a vise the jaws of which are at first kept closed by a series of springs which yield to receive the ends of the hammer heads but are afterward capable of being rigidly fixed upon any object between them by screws. When this sliding

10 frame descends it carries along with it the hammer heads in the clamp, the points of said hammer heads resting upon the strips of felt as seen at (a, b,) in Fig. VI, so that on being forced down the jaws part and effect the bending up of the felt upon the sides of the hammer heads, as seen in Fig. VII. At B is a narrow block extending from one end of the frame to the other, and

15 guided in its movements up and down by the upright pieces C. Upon its top edge there is a groove cut longitudinally from one end to the other as seen at (g) Figs. IV and V, within which groove is a series of

20 pulleys (g'). The groove is covered by a plate on which rests a series of short levers (h); one end of each lever is forked so as to receive a small pulley (h') as shown. All the levers are acted upon simultaneously by

25 means of a cord (i) weighted at one end, and rove through the two sets of pulleys (g' and h'). One end of each lever (h) supports a long narrow bar (k) extending from one end to the other of the machine.

30 The top edge of (h) is perfectly straight in the direction of its length, but has a slight hollow cut in it, as seen more clearly in the enlarged section Figs. VI, VII. The under-side terminates in a row of legs spaced so

35 that each leg shall rest upon one end of a lever (h), as shown. It will now be seen that the object of the levers and cord and weight (i) are for the purpose of keeping the top edge of the bar (k) pressing hard

40 against the points of the hammer heads (e). Thus the strips of felt (a, b,) on being laid upon the hollow in this bar, and the clamp A containing the hammer heads being pressed down so as to bring their edges

45 upon the felt, the latter will be held firmly between the two, viz, the top of the bar (k) and the ends of the hammer heads. The degree of pressure to be applied to this part is regulated by the weight (i') or a spring

50 or other power may be substituted. The bar (k) is kept in its vertical position by means of a number of braces consisting of thin strips of metal or other material, which extend down parallel to each leg and follow

55 the sides of B, passing around under its

bottom edge and up the other side to the bar again, as seen at (o) Figs. IV and V, partly in dotted lines. At (m) is a narrow bar which rests upon the bed of the machine; a slight sliding motion may be given to it 70 by means of a rod (m'). At (m'') are two studs carried by the bar, the tops of which may be brought to coincide with two other studs (o'), depending from the lower edge of B. Thus when (m'') is made to coincide 75 with (o') they form pillars upon which B may be supported by the bed of the machine, and when not so situated, but placed as in the drawings, B may be permitted to descend.

The clamp A with its hammer heads, bar (k), the piece B with its rollers, levers, &c. when fixed in certain positions, are capable of being moved connectedly in an unaltered position up and down between the main upright C of the machine. To effect this all 80 those pieces are attached to two guide frames which may be permitted to slide in guides attached to the upright C. These two frames are seen at (p), and (p') are 85 the gibs or grooves attached to C for the frames to slide in; (p'') are nuts attached to (p) to elevate and lower that by the screws and cranks (d'') as shown. The form of the frame is seen detached from the 90 machine at Fig. VIII. In the upper part is a slot dovetailed on the sides, as seen at (p) Fig. II. This receives the ends of the clamp A, which when put in are firmly held in place by keys (d'''). The lower part forms 95 a strap within which the block B rests, the opening being greater than the width of the block so that the latter may have some play within it, and at (p''') is a screw by which B may be raised or lowered as far as 100 permitted by the length of the strap. Suppose that A, (k), B, were out of the machine; then by turning the cranks (d'') the frame (p) would be raised or lowered. Now place B in the strap, the lower edge 105 resting upon the screws (p'''); then it is evident that B may be raised or lowered by the action of said screws. If (k) is now put in it will be raised or lowered by raising or lowering B by (p'''). Unscrew (p''') until 110 B rests upon the bottom of the strap. Now fix A with its row of hammer heads in the frame and key it with the keys (d''') so that it is firmly seated in place; there will then be a space between the lower edge of (e) 115 and the top or hollowed edge of the rail (k). Lay upon (k) the two strips (a, b,) of felt, then turn the screws (p''') and raise B; this carries up the levers (h) on which rests (k), and consequently that is carried up until 120 the strips of felt are brought to bear against the edges of the hammer heads (e); continue to screw up (p''') and the levers will begin to tilt, causing the cord (i) to be 125 stretched and thereby raise the weight (i'). 130

Thus every part of the hollow on (k) is pressed up equally against the felt, and that against the ends of the hammer heads with a power according to the weight of (i'). This pressure produces a good fit on the end of the hammer and properly shapes it as seen in Fig. VI. The glue is now to be applied to the ends of the felt and along the sides of the hammer heads as the latter lies spread out upon the mouth piece of the vise, as seen more plainly in Fig. VI at (a, b). As soon as this is done, the two cranks (d'') are turned around and the two pieces (p) are made to descend carrying with them in the relative positions just described, A (k) B; the piece (k) slipping from between the lips of the vise, while the hammer heads follow, and the lips pressing up the glued sides of the felt against the sides of the hammer heads until they come into the positions shown in Fig. VII. After the gluing has been completed the frame (p) is raised, lifting the hammers out from between the jaws of the vise, which is attached to the permanent frame as hereafter described, the piece (m) is then moved so that (o') rests upon (m'') and there supports B. The points of the screws (p''') are now taken from under B or screwed down as far as they will go; this operation permits the frame (p) to be still further carried up without taking B with it, and as the clamp A is fixed to the top of (p) this effects the clearing of the ends of the hammers from (k), when the keys (d''') being removed the clamp can be taken out and a fresh set of hammer heads introduced to be acted on as before.

This brings me to the construction and operation of the second part, viz, the vise. The jaws are formed of bars placed vertically at a little distance apart and parallel to each other, as seen at (r). Below the lip pieces they are bent outward so as to allow the block B to play between, as seen in Fig. V. The several pieces (r) are fastened at the bottom to a continuous strip (r') and at the upper part they are connected together by another piece (r'') let in on the inside face of the ends. This piece should be of metal as it is by this the bite or grip is given upon the lips. The lips (s) are right angled strips and should be of metal; these lie within and rest upon the top corner of the jaws formed by (r''), as shown in the several figures and more clearly in the enlarged view at Figs. VI and VII. It will be observed that these inside faces which embrace the plate (k) are slightly angled. This is for the purpose of embracing the felt after the head of the hammer has been pushed through and producing an equal pressure upon the sides of the hammer heads, or along all that part where the glue has been applied (no glue being put upon

the point or extreme end, as that would injure the elasticity of the felt). This operation is more particularly shown in Fig. VII. Upon the horizontal angle of the lip pieces are laid two other pieces which may be of wood, as seen at (s'), having the inside surfaces beveled as shown in Fig. VI. These form the gluing tables, and support the edges of the felt while the brush and glue are applied, as clearly seen. They can be taken off to be cleaned whenever the waste glue accumulates sufficiently to require it. In the first part it was stated that while the set of hammer heads and the strips of felt were being carried down between the lips of the vise, the jaws of the latter were all the time pressing hard upon the felt to secure the proper contact of the felt with the hammer heads and thus insure the perfect gluing of the parts. This is effected by a series of levers and springs arranged as follows: Along the sides of the jaws of the vise, but so as to leave a narrow space between the two, are arranged a number of vertical posts (t). The lower ends of these are framed in the pieces (r'), the tops being strongly braced together by the strips (t'). This outside frame forms a kind of secondary vise, as it also may be sprung together a short distance, the pieces (t'') Fig. V forming the lips which press against the top of the jaws (r). This pressure is produced by acting upon the nuts (u) to a row of bolts (u') which pass through from side to side in holes made in the piece (t). Between the several posts (t), are a system of levers (v) having their fulcra in the upper end of the frame (t'). The weight or force acting upon the levers consists of a series of springs (w). These may be, and as represented are, bands of rubber rove through and looped into pegs formed upon the bottom of each lever by sawing out several slots, as clearly shown at (w') Fig. I. These bands pass through slots cut in the lower ends of the pieces (r) forming the jaws of the vise, so that the latter shall interpose no obstacle to their free working. The power or pressure is applied at a central support (x). This is a projecting rib extending along the whole of the levers and secured to a flat piece or flange (x') which rests against and bears upon the uprights (r), forming the jaws of the vise. A side view is given in dotted lines in the sectional Fig. IV and an end view in Fig. V. Now it will be seen that the springs (w) drawing upon the ends of the levers (v) whose fulcra is (t') will press upon the pieces (x) and thus again press upon the uprights (r) forming the jaws of the vise and therefore press the lips (s) together as before described. Hence as the bar (k) descends followed by (e), holding between them the felt (a, b), the latter by the pressure of (s) 130

must be bent up and kept hard pressed against the sides of (e). The degree of pressure produced by the springs (w) may be increased or diminished by shifting the 5 place of (x) along the levers (v), to increase, the pressure (x) must be brought toward the fulcrum (t'), and vice versa. This is accomplished by supporting (x') upon a second piece (y) the upper edge of 10 which is cut to form several inclined planes (y'), the piece (x') also being notched to fit as seen at (y'). A pawl and ratchet regulates the several heights to which the bar (x) is to be raised. The bar (x) and 15 (x') can only play up and down, while (y) may move laterally or at right angles to (x') and (y) is supported upon studs (y''). The ratchet is at (z) and the pawl at (z') attached to (x'). To move (y) in order to 20 raise (x) draw the rod (z''') until the end of the pawl (z') falls into the first notch (z), this causes (x') to slide up the plane or angle (y'), thus (x) is elevated to any position desired. To lower (x) raise the 25 pawl (z') which can be done by a small rod (z'') reaching to the top of the machine and thus withdraw (y) to the point desired. After the hammer heads (e) and the felt have been pressed between the jaws of the 30 vise in the manner before described, and as shown in Fig. VII, the pressure must be increased upon the felt to a greater degree than that produced by the action of the springs (w) and levers (v). This is ac- 35 complished by tightening the nut (w) upon the bolts (u'), which action springs the outer frame toward the center and brings the pieces (t'') to bear against the top of (r), and the jaws and lips (s) are clamped 40 upon (e) with any pressure desired. This pressure is maintained until the glue has fully "set" or become hard enough to allow of the removal of the hammers. As soon as the pressure is finally given by the screws 45 and bolts (u, u'), the pressure upon the end of the felt produced by the hollow in the plate (k) must be taken off, because if it were maintained it would mar the hammer and unduly harden it. To accomplish this 50 it is only necessary to lower B by means of the screw (p''') as before described, and as (k) rests upon B through the intervention of the levers (h) that accordingly de- 55 scends also leaving A and (e) stationary in the jaws of the vise, and therefore all clear. In order to avoid the necessity of working the screws (p''') the distance required for the movement of B, I shorten the operation by resting B upon blocks B'' so that by 60 loosening the screws a little the block may be withdrawn and B will descend the distance required, the studs (m'') being re- 65 moved from under (o'). After the glue has become hard the hammers are removed.

65 To do this all the pressure must be taken off.

The screws (u) are first loosened to relieve the outside clamp (t). The spring pressure upon the jaws must also be taken off, so as to allow the hammers to slip from between the lips without obstruction, as otherwise 70 there would be a risk of having the felt torn off again. The lower ends of the levers drop into a groove (z''') formed in a table running the whole length of the machine, this table rests partly upon brackets outside and 75 partly upon the bed of the frame itself. A slight horizontal play may be imparted to it, as shown by the dotted lines in Fig. III, and where also a space is cut out of the brackets to allow it, the levers must be 80 spread apart by pushing out these grooves (z'''), which when done takes the pressure off of the rib (x) and therefore from the jaws also. This is done by means of several small toggles (j) seen in Fig. II one end of 85 each of these rests in a sliding bar (j'') and the other end acts against the back part of the shelf in which the groove (z''') is situated. The bars (j'') are coupled to a lever and treadle on the outside of the machine 90 at F. By pressing down the treadle as seen in Fig. I the two bars (j'') will be drawn along, this will straighten the toggles (j) Fig. II and push out the groove (z''') 95 carrying with it the ends of the lever (v) and thus relieve the pressure on the jaws (r). The two handles (d'') must now be turned to raise up the frame (p) and all the pieces depending upon its movements until the two studs (o) are sufficiently high to 100 allow the studs (m'') to go under. The hammers will then be lifted out clear of the jaws, the top of (k) will be in place to receive the next strips of felt for additional coats; if no others are to be applied then the clamp A may be removed for taking out the 105 finished hammers and receive a new set of hammer heads. The strips of felt are now laid on as before, the clamp A must be lowered to bring the edges of the hammer heads to press on the felt. This is done by turning the handles (d'') again, which lowers the frame (p), the block B remains stationary, resting upon the studs (o' m'') 110 by which means the grooved top of (k) is maintained just above the mouth of the vise as shown in the several figures. The points of the hammer heads (e) are again pressed upon the felt as before. The two screws (p''') are now to be brought to bear against 115 B in order to keep (k) pressed against (e), (the felt being between), this done the glue is to be applied as before described, the posts (m'') withdrawn, the pressure of the 120 springs applied to the jaws of the vise, the slides (p) made to descend carrying the felt (a, b,) and point of the hammer heads (e) 125 between the lip pieces, and the operation completed as before set forth.

What I claim as of my own invention, and 130

desire to secure by Letters Patent of the United States, is—

1. The application of the felt or other covering material to the whole set of hammer heads at one operation in the manner described.
2. I claim the clamp A, bar (k), levers, pulleys, and block B with the sliding frame (p) in combination substantially as described, but without limiting myself to the precise shapes and proportions or positions of the said parts, provided the arrangement embrace the means of holding the set of hammer heads and of bringing them to bear upon a table containing the strips of felt described and also the holding and moving the whole together either horizontally or vertically to and from the jaws of the vise as set forth.
3. I claim the vise in combination with

and inclosing the bar (k) and block B as described.

4. I claim the lip pieces in combination with said vise for the purpose described.

5. I claim the levers and springs in combination with the vise for producing the pressure upon the sides of the felt during the passage of the hammer heads between the jaws of the vise as described.

6. I claim the method of increasing or diminishing the pressure of the levers upon the vise by means of the movable bridge (x) in combination with the press (x') and (y) as described.

The whole being constructed and operating substantially in the manner described.

RUDOLPH KRETER.
